UNITED STATES PATENT OFFICE.

WILLIAM F. COLE, OF WACO, TEXAS.

APPARATUS FOR FORMING GUN-BARRELS.

1,339,023.

Specification of Letters Patent.

Patented May 4, 1920.

Application filed September 10, 1917. Serial No. 190,600.

To all whom it may concern:

Be it known that I, WILLIAM F. COLE, a citizen of the United States, and a resident of Waco, in the county of McLennan and State of Texas, have invented a new and useful Improvement in Apparatus for Forming Gun-Barrels, of which the following is a specification.

My present invention relates generally to the manufacture of gun barrels, and particularly to the manufacture of gun barrels having smooth bores of elliptical shape, twisted uniformly and adapted to replace gun barrels having the usual internal rifling. Gun barrels formed and shaped as above, as shown for instance in my Patent 694833 of March 4, 1902, possess considerable advantage over gun barrels rifled as usual, in certain respects, although up to the present time the cost of production has been a decided disadvantage of this type of gun barrel, and it is therefore the primary object of my invention to provide a simple inexpensive apparatus or mechanism capable of avoiding the disadvantage named, and of imparting the desired shape or form to a gun barrel in a quick, effective and economical manner.

Generally speaking, my invention provides an apparatus whereby a cylindrical tube may be slightly flattened along a uniform helical line for either its entire length or the greater proportion of its length, this shaping of the gun barrel taking the place of the usual step in the manufacture of gun barrels which consists in grooving the wall of its bore along helical lines. The particular means proposed by my invention for this purpose consists of a pair of forming plates disposed and held at all times in parallel planes, between which a truly cylindrical tube is disposed in such manner as to permit of its free and ready rotation upon its longitudinal axis during the forming operation, the plates having angularly disposed ribs between which the tube is pressed during the movement of at least one of the plates whereby the oppositely disposed ribs will have a constantly shifting contact with the tube during the rotation of the latter and will define along the line of contact, the lesser diameter of the elliptical portion of the tube.

My invention therefore resides specifically in the apparatus to be now described with reference to the accompanying drawings,

forming a part of this specification, and wherein:

Figure 1 is a plan view illustrating the apparatus constituting my invention. 60

Fig. 2 is a side elevation thereof.

Fig. 3 is a plan view, reduced, with one of the plates shifted with respect to the other from the position shown in Fig. 1.

Fig. 4 is an enlarged vertical sectional view taken substantially on line 4-4 of Fig. 3. 65

Fig. 5 is an enlarged cross section through a tube illustrating its truly cylindrical shape before action thereon by my improved apparatus, and 70

Fig. 6 is a similar view through a tube after it has been acted upon by my improved apparatus and after its outer surface has been turned to truly cylindrical shape once 75

more.

Referring now to these figures, I propose the provision of a pair of forming plates 10 and 11, the former of which may be secured and held in any desired manner upon a stationary support generally indicated at 12, and is provided at one side with an up-standing portion 13 which may be either a ledge extending the full width of the plates, or lugs at spaced points thereon as desired, 85 and the function of which will be presently made plain.

The other plate 11 is disposed above the plate 10 and is movable with respect thereto and held in a plane parallel with the plane 90 of the plate 10 at all times. This movable plate 11, whose shifting in operation may be brought about by any suitable power mechanism and connection, including for instance a pitman 14 connected to one side of the plate, may be suitably guided in its movements, as for instance, by side parallel grooved guide members 15.

It may be here stated, that both of the plates 10 and 11 may be moved if so desired, 100 but this being unessential as presently described, I deem it more simple and economical to position the plate 10 in a stationary manner and accomplish the desired operation by the movement of plate 11 alone. 105

The plates 10 and 11 are provided with rounded projecting ribs 16 and 17, respectively, each extending generally in a transverse direction and at an angle to the longitudinal axis of the plates, these ribs being 110 rounded transversely and provided with smooth surfaces, so that by properly spac-

ing the plates with respect to one another, a truly cylindrical tube 18 may be disposed therebetween to rotate freely upon its longitudinal axis as it is engaged by the ribs 5 16 and 17.

By reference to Figs. 1 and 3 in particular, it will be noted that the ribs 16 and 17, projecting toward one another from the plates 10 and 11 are disposed at divergent 10 angles, and thus upon disposition of a tube 18 against the angular up-standing portion 13 of the plate 10, and movement of the plate 11 in the direction of the arrow of Fig. 2 across the plate 10, the ribs 16 and 15 17 will engage the tube along a constantly shifting although uniformly helical line, and by flattening the same slightly as seen in Fig. 4, will define the lesser diameter 20 of the finished elliptical tube having its ellipse uniformly twisted. This is to be seen plainly by a comparison of Figs. 1 and 3, the latter figure of which shows the upper plate 11 advanced over the plate 10 with respect to the positions of these plates in 25 Fig. 1.

After the desired shape has been imparted to the tube 18 as above described, it may be removed and placed in a lathe in order that its outer surface which at this 30 time is obviously of the same general shape as its bore, may be turned to truly cylindrical form once more, as seen in the finished gun barrel 19 of Fig. 6, the bore 20 of which, of course, remains in the shape imparted in the action of my improved apparatus.

It is obvious that any suitable movable support may be provided for engaging the extremities of the tube 18 disposed between 40 the plates 10 and 11 as shown in Figs. 1, 2 and 3, capable of confining movements of the same to a uniform rolling motion as it advances slightly across the rib 16, so as to prevent all danger of one end shifting 45 with respect to the other.

It is furthermore obvious from a consideration of the foregoing, that the pitch of the helical slightly flattened line of the tube may be controlled by varying the angular 50 disposition of the ribs 16 and 17, and that while the details may be variously changed, the essentials of an apparatus of the present type are as shown, and the general relation of the parts will remain as described.

55 I claim:

1. An apparatus for forming gun barrels, including a pair of spaced apart parallel forming members, one at least of which is movable, and between which a 60 truly cylindrical tube may be disposed to freely move with the movable member and rotate on its longitudinal axis in a plane at right angles to the plane of movement

of the movable member, said members having angularly disposed forming ribs projecting toward one another to engage the tube so disposed at a constantly shifting point in its length, for the purpose described. 65

2. An apparatus for forming gun barrels including a pair of spaced apart parallel forming members, one at least of which is movable, and between which a truly cylindrical tube may be transversely disposed to freely rotate on its longitudinal axis and roll at right angles to this axis with the movement of the movable member, said members having forming ribs projecting toward one another and disposed at divergent angles whereby to engage the tube so disposed, along a line constantly shifting longitudinally and circumferentially of the tube. 70 75

3. An apparatus for forming gun barrels, including upper and lower spaced apart forming plates having generally transverse ribs extending toward one another, and one of which plates is movable in a plane parallel to the plane of the other plate, said ribs being disposed at divergent 80 angles with respect to one another, and guides for the movable plate arranged to maintain parallel relation between the plates at all times. 85 90

4. An apparatus for forming gun barrels including upper and lower spaced apart forming plates, one of which is movable in a plane parallel to the plane of the other plate, guides for the movable plate, and forming ribs carried by said plates and projecting toward one another in the space between the plates, said ribs being disposed at angles diverging toward one side of the plates, for the purpose described. 95 100

5. An apparatus for forming gun barrels including a pair of forming members, one of which has bodily shifting movement parallel to the other, said members being provided with forming ribs extending toward one another, and being so spaced and related as to permit a tube disposed therebetween to freely roll with the movement of the movable member and present a constantly shifting point of contact with the forming ribs. 105 110 115

6. An apparatus for forming gun barrels, including a pair of forming members, one of which has bodily shifting movement parallel to the other in spaced relation to receive therebetween a tube to be formed 120 and permit the tube to roll freely with the movement of the movable member said members having means to engage the tube at a point constantly shifting lengthwise of the tube during its movement.

WILLIAM F. COLE.
